*Daniel Young,
A. P. Mattingly.*

By his Attorney

UNITED STATES PATENT OFFICE.

DANIEL YOUNG, OF BROOKLYN, NEW YORK, ASSIGNOR TO YOUNG INVENTIONS, INC.,
A CORPORATION OF NEW YORK.

HOSIERY.

Application filed August 19, 1922. Serial No. 582,925.

To all whom it may concern:

Be it known that I, DANIEL YOUNG, a subject of the King of Great Britain, and resident of Brooklyn, in the county of Kings and 5 State of New York, have invented certain new and useful Improvements in Hosiery, of which the following is a specification.

This invention relates to improvements in hose or stockings such as are worn by men, 10 women and children, and is especially adapted for that style known as the half hose or stocking.

The objects of this invention are to provide a hose or stocking of this character, 15 which will conveniently and easily adjust itself to the leg and which is comfortable to the wearer, and does not unnecessarily bind or pinch the leg; but has a light and clinging effect thereto, without the use of an 20 additional support such as is in use at the present time.

The further objects are to provide a stocking of this character which is so constructed that it will obviate the necessity of rolling 25 the tops of the stockings to hide the garters which are now used.

It will be seen I accomplish the foregoing by referring to the drawings forming a part 30 of this specification in which Fig. 1 is a side elevation of the upper part of my improved hose or stocking; Fig. 2 is an enlarged dia- 35 grammatic sectional view of a portion of the upper part or top of the hose or stocking, and is greatly exaggerated as regards the threads of which it is constructed; Fig. 3. is a similar view to Fig. 2., but showing a 40 different form for obtaining the same result; Fig. 4. is a similar view to Figs. 2 and 3., but showing another form to obtain the same result; Fig. 5. is a similar view to 45 Figs. 2, 3 and 4., but showing another form to obtain the same result.

Referring to the drawings which show a general embodiment of this invention and it 50 being understood are more or less diagrammatic of a knitted hose, it will be seen there can be many changes in the general form of construction without departing from the spirit of my invention, and it will be understood that the principal point of this invention is to provide a hose or stocking having a top so formed that it will cling to any part of the leg whether it is located above or below the knee, and does not depend on any

subsidiary member to retain it in the position in which it is placed, and the top being so retained that it will securely support the rest of the stocking, and cause it to snugly fit the leg of the wearer. 55

Referring to the drawings it will be seen 60 I provide a hose or stocking 2 having the regular leg portion 3 of the usual construction, which is made by the threads interlocking with each other to make the smooth or body portion of the hose or stocking which 65 terminates as indicated by the dotted line at 4, where the top portion 5 of the hose or stocking begins, and the construction may be changed to form vertical or raised portions, and for convenience I will term these 70 portions ribs, and if the ribs are used they will be similar to the ribbed tops now in use, and it will be understood that this ribbed portion is made up of the same two threads or continuation of them until a predetermined portion of the top is formed as at 6, when another thread is interposed by the fraying of its end, and twisting the frayed portion or end around one of the original threads, so as to cause it to be carried along 75 in the constructing process, and thus cause a thicker material to be made of a tighter construction, and the exerting of a greater tension on the threads will cause the diameter of the top to decrease as at 7, this action 80 will take place, although the same number of needles are used in making the upper and lower part of the top, or in other words there are the same number of stitches in the diameter of the top at 8, as there is at 9, and 85 the difference of the diameters are caused by the extra tension on the material or threads at 8, and thus decreasing of the diameter. It has been found that the interposing of this extra thread gives an exceedingly good result, 90 especially in woolen stockings; but I prefer 95 to interpose a second extra thread in the same manner as the other extra thread, after 100 a few rounds of the top have been made or formed with the interposing of the first extra thread, as is shown in Fig. 3, and thus further thickening the portion 8, and still further decreasing its diameter, and where silk or lisle are used in making the 105 hose or stocking, I will multiply the number of these interposed threads to any desired number, and it will be understood that the finer the threads of which the stocking is

made, the greater number of interposed threads will be required to get the proper thickness, and decreased diameter of the part 8 as shown in Fig. 3.

5 It will be further understood that I can obtain the same result as already described (as regards to using the multiplied number of interposed threads for silk or lisle stockings) by interposing a woolen thread of a 10 larger diameter or a thread of the same material; but of a larger diameter, or by splicing threads of a larger diameter to the two original threads and finishing the top with the two threads of the larger diameter.

15 It will be still further noted that I can obtain the foregoing results in the following manner, as shown in Fig. 5, and it will be seen in this case that I interpose threads 10 of a different material and texture from 20 the threads 11 which are used to form the main or body portion of the stocking, and for illustration I will state if the stocking is formed of silk or lisle, the interposed threads may be made from wool or cotton,

25 or a mixture thereof, and in the construction the needles are made to operate so as to cause the woolen thread (if wool is used) to be so positioned as to cause it to form a lining 12 on the inside of the stocking, and 30 not to show on the outside of the stocking, and it will be noted that the silk threads will be so drawn, in order to hold the woolen threads in position as to cause the decreased diameter of the part 8.

35 The operation or action of this hose or stocking is very simple, and it will be noted that when the stocking is drawn on the leg, that the upper and stronger portion will necessarily have to be stretched more owing 40 to the contracted upper portion, than the other part thereof, and being thicker it will be less elastic, and will cling tighter to the leg, and hold the stocking securely in position, and the movement of the leg will 45 cause the thinner part of the stocking to move or slip, as the thinner part will give more readily to the movement of the muscles of the leg than the thicker part, and

thus the thicker portion will cause the thinner portion to return to its stretched or normal position, and the stocking will always stay in a smooth and snug position.

50 What I desire to claim is:

1. An article of manufacture, a hose having a body portion and an upper cuff portion, said cuff portion at a plurality of adjacent points throughout its length being of greater thickness and strength than said body portion thereby offering increased resistance to expansion of the cuff portion, the inside 60 diameter of said cuff portion being less than the inside diameter of the adjacent part of said body portion.

2. An article of manufacture, a hose having a body portion and an upper cuff portion, said cuff portion from the body portion upward being of greater progressive thickness than said body portion thereby offering increased resistance to expansion of the cuff portion, the inside diameter of said cuff portion being less than the inside diameter of 70 the adjacent part of said body portion.

3. An article of manufacture, a hose having a body portion and an upper cuff portion, said cuff portion having a progressive 75 increasing number of threads providing a cuff portion of greater thickness and strength than said body portion thereby offering increased resistance to expansion of the cuff portion, the inside diameter of said 80 cuff portion being less than the inside diameter of the adjacent part of said body portion.

4. The method of forming a hose having a body portion and a cuff portion, which 85 consists in constructing the body and cuff portions each of a plurality of threads and introducing into the cuff portion a plurality of progressively increasing number of threads under greater tension than the tension of said first named threads.

90 Signed at New York, in the county of New York and State of New York, this 1st day of August A. D. 1922.

DANIEL YOUNG.
